(57) **CLAIM**

The ornamental design for a set of nose cones, as shown and described.

DESCRIPTION

FIG. 1 is a perspective view of a set of nose cones for use with anesthesia apparatus for laboratory animals, the first component being a nose cone for large laboratory animals, the second component being a nose cone for use with medium sized laboratory animals, and the third nose cone for use with small laboratory animals;

FIG. 2 is a front elevation of the first component of the set of nose cones, the top plan and bottom plan views being identical, a lefthand portion of the component being broken away to illustrate the thickness of the sidewall of the component;

FIG. 3 is a left side elevational view of the first component shown in FIG. 2;

FIG. 4 is a right side elevational view of the component shown in FIG. 2;

FIG. 5 is a front elevation of the second component of the set of nose cones, the top plan view and the bottom plan view being identical, a portion of the lefthand end of the drawing being broken away to illustrate the thickness of the side wall of the component;

FIG. 6 is a left side elevation of the second component shown in FIG. 5;

FIG. 7 is a right side elevation of the component shown in FIG. 5;

FIG. 8 is a front elevational view of the third component of the set of nose cones, the top and bottom plan views thereof being identical, a portion of the lefthand end of the drawing being broken away to illustrate the thickness of the sidewall of the component;

FIG. 9 is a left side elevation of the third component shown in FIG. 5.

FIG. 10 is a right side elevation of the component shown in FIG. 5; and,

FIG. 11 is a front elevation of the first component of the set of nose cones showing its attachment to an anesthesia machine indicated in broken lines in FIG. 11.
